(57) CLAIM
The ornamental design for a Christmas stocking shaped merchandise display, as shown and described.

DESCRIPTION

FIG. 1 is a perspective view of a Christmas stocking shaped merchandise display showing my design, the display shown with a peg hook;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines shown in FIG. 1 of a peg hook and the broken lines of the holes in the drawings are directed to environment and unclaimed subject matter, and are for informational purposes only and form no part of the claimed design.

1 Claim, 2 Drawing Sheets

FIG. 6

FIG. 7
